DESIGN FOR A TRAY OR SIMILAR ARTICLE

Samuel Guzman and Herbert Rappaport,
New York, N. Y.

Application May 17, 1946, Serial No. 129,773

Term of patent 14 years

(Cl. D44—14)

To all whom it may concern:

Be it known that we, Samuel Guzman and Herbert Rappaport, both citizens of the United States, both residing at New York, in the county of New York and State of New York, have invented a new, original, and ornamental Design for a Tray or Similar Article, of which the following is a specification, reference being had to the accompanying drawing, form a part thereof.

In the drawing:

Fig. 1 is a top plan view of a tray or similar article showing my new design;

Fig. 2 is a side elevational view of the same; and

Fig. 3 is a vertical sectional view taken on the line 3—3 of Fig. 1.

We claim:

The ornamental design for a tray or similar article, as shown.

SAMUEL GUZMAN.
HERBERT RAPPAPORT.
